(57) **CLAIM**

The ornamental design for a camera, as shown and described.

DESCRIPTION

FIG. 1 is a front, right side, perspective view of a camera showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 shows the protective cap for camera partially covering a camera;

FIG. 9 shows the protective cap for camera separated from the camera; and,

FIG. 10 shows the protective cap for camera and camera in an alternate position.

The broken lines in FIG. 7 depict unclaimed portions of the camera and form no part of the claimed design. The broken lines in FIGS. 8-10 showing a protective cap depict environmental subject matter and form no part of the claimed design.

1 Claim, 9 Drawing Sheets
